SCOREBOARD

Ralph Arthur Nevinger, Greenville, Ill.

Application July 2, 1935, Serial No. 29,560

1 Claim. (Cl. 161—7)

This invention relates to scoreboards and more particularly to scoreboards of the electrically operated type, designed primarily for scoring the points of the game of basket ball.

5 An important object of the invention is to provide an electric scoreboard which may be operated by an attendant operating an electrical switch, the mechanism of the scoreboard being such that the score, quarter being played and 10 number of remaining minutes to play, will be displayed so that an accurate reading of the scoreboard and complete standing of the opposing teams may be readily determined.

15 A further object of the invention is the provision of means to cause an audible signal to be made when the scoreboard is operated to indicate "time out" or when the time for playing is becoming short.

20 A still further object of the invention is to provide a mechanical scoreboard wherein the dials may be readily returned to their initial positions when it has been found that the scoreboard has been operated to display the score incorrectly.

25 With the foregoing and other objects in view which will appear as the description proceeds, the invention consists of certain novel details of construction and combinations of parts hereinafter more fully described and pointed out in 30 the claim, it being understood that changes may be made in the construction and arrangement of parts without departing from the spirit of the invention as claimed.

Referring to the drawings

35 Figure 1 is an elevational view of a scoreboard constructed in accordance with the invention.

Figure 2 is a side elevational view of the clock mechanism, forming a part of the scoreboard.

40 Figure 3 is a sectional view taken on line 3—3 of Figure 2.

Figure 4 is a sectional view taken on line 4—4 of Figure 2.

Figure 5 is a plan view of one of the switch boxes.

45 Figure 6 is a plan view of the switch board operated by the score keeper.

Figure 7 is a rear elevational view of one of the dials, illustrating the contact member at the rear of the dial.

50 Figure 8 is a partly sectional side elevational view of one of the dials and housing structure.

Figure 9 is a plan view of one of the dials.

Figure 10 is a diagram illustrating the various electrical circuits of the scoreboard.

55 Referring to the drawings in detail, the cabinet

of the scoreboard is in the form of a housing embodying a lower section 5 and an upper section 6, the housing or cabinet being formed with display openings A and B in the front wall thereof, arranged in pairs, the openings of each pair being arranged in close proximity for purposes to be hereinafter more fully described.

Mounted within the lower section 5 of the cabinet, are dials 7 and 8, which are formed of suitable translucent material and supplied with indicia on the outer surfaces thereof to be viewed through the display openings as the dials are rotated, the indicia representing the score of the game being played. While I have shown two sets of these dials as mounted within the cabinet, 10 one set of dials representing the score of the home team and the other set of dials representing the score of the visiting team, and because both sets of dials are identical and operated in the same manner, only the set of dials representing the 15 home team and circuits controlling these dials, will be described.

As clearly shown, these dials 7 and 8 are mounted on shafts 9 which extend through openings in the uprights 10, forming a part of the 20 frame structure of the cabinet or housing, the dials being mounted for rotary movement on their shafts. Secured to the rear surface of each of the dials is a disk 11 constructed of insulating material, which disks are supplied with 25 contact plates 12 formed with cutout portions 13 providing spaces exposing portions of the insulating disks.

The numeral 14 (Fig. 10) indicates the power 30 wire of the electric circuit controlling the motors and lamps of the scoreboard. As clearly shown by the drawings, the wire 14 extends into the main switch box 15 where it connects with the contact point 16 of the switch 17, which is of the key operated type. The wire 18 connects with the 35 switch member 18' which is engaged by the switch member 17, when the key is operated to close a circuit. This wire 18 extends to a position where it is in circuit with the shafts 9, through the wires 19 and 20.

The wire 18 provides the positive wire of the 40 motor circuits of the device. Associated with the contact plate of the dial 7, is a contact arm 21 which is supported by an upright 10 and insulated therefrom, which contact arm wipes the 45 contact plate of the dial 7, completing a circuit. Under normal conditions the contact arm 21 rests in a cutout portion of the contact member between sections of the contact plate, breaking the circuit to the motor associated with the dial. 50 55

Connected with the contact arm 21 is a wire 22 through which current flows to the motor 23 that operates the dial 7, through the roller frictionally engaging the periphery of the dial 7 5 rotating the dial 7, as shown by Figure 1 of the drawings.

The motors are mounted on the pivoted supports 25 (Fig. 1) and the rollers 24 mounted on the shafts of the motors are held into engagement with the dials, by the weight of the motors. Wire 26 connects with the motor 23 and connects with a terminal 27 to which the wire 28 is connected, the wire 28 leading into the control switch 29, where it connects with the contact member 30. The switch member 31 is adapted to engage the contact member 30 completing a circuit between the switch member and wire 18, through the wire 32 which connects with the wire 18 and provides the return wire of the circuit to the motor 23. The motor 23 is also in circuit with the negative wire 33 through wires 34, 39 and 35'. Thus it will be seen that when the switch member 31 is operated to complete the circuit to the motor 23, current flows directly to the motor 23, through the wires 28 and 26, through the motor and through the wires 34, 35' and 33. The dial 7 now rotates slightly, causing the contact arm 21 to ride out of the cutout portion of the contact plate, and engage the contact plate completing the circuit to the motor through the wires 18, and 20, contact disk, contact arm 21 and wire 22. The motor continues to operate, rotating the dial until the contact arm drops into the next adjacent space of the contact disk, whereupon the contact arm again rests on the insulation between the contact sections, breaking the circuit to the motor and causing the dial to discontinue its rotary movement. The next number of the dial is now presented to view through the display opening of the housing, representing a change in the score.

In circuit with the contact plate 12, is a contact member 35 which is arranged directly opposite to the number 2 of the dial 7. A contact arm 36 wipes the periphery of the disk 11 and is adapted to engage the contact member 35 completing a circuit to the motor 36' through the wires 37 and 38, the return circuit being completed through the wires 39 and the wires 35' and 33. Contact arm 41 wipes the contact plate 12 of the dial 8 completing the circuit to the motor 36' which continues to operate the dial 8 until the adjacent number of the dial is exposed through the display opening. When the contact arm 41 drops into a cutout portion of the dial 8, the circuit to the motor 36' will be broken and the motor 36' will cease to operate. Thus it will be seen that with each complete revolution of the dial 7, the dial 8 will be moved to bring a number thereof to a position to be viewed through the display opening.

The upper and lower sections of the cabinet are illuminated by the lamps 42 positioned within the cabinet, the lamps 42 lighting when the key switch of the switch box 15 is operated, the lamps receiving their electric current through the wire 42', which connects with the wire 18, and is in circuit with the switch 17, and wire 14.

Mounted in the upper section 6 of the cabinet 70 is a clock 43, which is of the electrically operated type, the clock being provided with a minute hand 44 and a second hand 45, the dial of the clock being supplied with numbers ranging from 1 to 8, the spaces between the numbers representing minutes, to the end that with each com-

plete rotation of the minute hand, one eight minute quarter of the game, has been played. It will of course be understood that this dial may be changed to meet the requirements of play of any game for which the device has been designed.

The clock includes a frame embodying plates 46 and 47 supported in spaced relation with each other. The main shaft of the clock is indicated by the reference character 48 and is operated by the clock mechanism, through the gears 49 and 50. The shaft 51 supports the second hand which makes one complete revolution every minute, while the shaft 48 supports the minute hand that makes a complete revolution every eight minutes, which is the length of a quarter.

Directly below the shaft 48 is a shaft 52 on which the gear 53 is mounted, which gear receives rotary motion from the shaft 48, through the gear 54 that meshes therewith. Carried by the gear 53, is a contact arm 55 that wipes the contact segments 56 supported within the frame, and insulated from the frame by means of the insulating block 57. These contact segments 56, are in circuit with the lamps 58, 59, 60 and 61, respectively, which lamps are arranged within compartments 62 that are disposed on opposite sides of the clock housing, the compartments being supplied with translucent front walls so that light rays from the lamps may illuminate the numbers carried thereon, which numbers indicate the quarters of the game. In order to identify the contact segments with their particular lamps, the segments are numbered 1, 2, 3 and 4. The segment 1 is in circuit with the lamp 58, through the wire 63, the return wire of the circuit being indicated by the reference character 64 which is in circuit with the wire 65 that in turn connects with the wire 35 leading to the wire 33. The circuit is completed to the segment 1, through the arm 55 which wipes the segments, the arm 55 receiving electric current through the shaft 52 which is engaged by the arm 66 that in turn is in circuit with the power line or wire 14, through the wire 67, which connects with the wire 68 that connects with the wire 18 leading into the switch box. From this point the current flows through the wire 14 completing the circuit and causing the lamp 58 to illuminate a compartment indicating that the first quarter is being played.

The gearing for operating the contact arm 55, is so constructed that with each complete revolution of the minute hand 44, the contact arm 55 will move throughout the length of one segment to the end that the lamp in the compartment indicating the quarter being played will remain lighted for a period of eight minutes.

When the second quarter is being played, the contact arm 55 will rest on the segment 2 which completes the circuit to the lamp 59, through the wire 69, wire 65, wire 35, wire 33. The return line of the circuit being through wire 67, wire 68, wire 18, switch box 15, and wire 14.

When the third quarter is being played, contact arm 55 rests on segment number 3 completing the circuit through the wire 70, wire 65, wire 35 and wire 33, the return line of this circuit being through the arm 66, wire 67, wire 68, wire 18 into the switch box 15, and through wire 14. When the fourth or last quarter is being played, the contact arm 55 moves to engage segment number 4, lighting the lamp 61, which is colored red to further accentuate the fact that the time for play is short. When the arm 55 engages segment number 4, the circuit 75

is completed to the red lamp 81, through the wire 71, wire 65, wire 35 and wire 33, the return line of this circuit being through the arm 86, wire 67, wire 68, wire 18 through the switch box 15 and power line 14.

When it is desired to start play, the switch arm 72 is moved to engage the contact member 73, which is in circuit with the clock motor, through the wires 74 and 75, the return wire of this circuit being through the wire 98 that connects with the wire 33.

Mounted on the shaft 77 of the clock frame, is a disk 78 formed of insulating material, the disk 78 being mounted to rotate with the shaft 77, which is rotated through the gears 79 and 80. Mounted within the clock frame, is a pivoted contact arm 81 which is in circuit with the wire 67. This contact arm 81 normally engages the contact arm 82 which is in circuit with the white lamps 89' of the clock cabinet, through the wire 83, the circuit also including the wires 84, wire 35', and wire 33. The return circuit is made through the wire 85 which connects with the wire 67, the wire 68, wire 18, switch box 15, and through the wire 14. The disk 78 is formed with a substantially long, cutout portion 86 disposed in the periphery thereof, the cutout portion permitting the finger 87 of the pivoted contact arm 81, to move downwardly with the result that the contact arm 81 will engage the contact arm 88, breaking the circuit to the lamps of the cabinet, and completing the circuit to the red lamps 89 of the cabinet, the circuit being made through the wire 90 which connects with the wire 35' that in turn connects with the wire 33. Mounted on the shaft 77, in spaced relation with the disk 78, is a disk 91, which is also constructed of insulating material, the disk 91 being mounted on the shaft 77 to rotate therewith. This disk 91 is formed with a cutout portion 92 disposed in its periphery. Under normal conditions, the electric circuit to the clock motor is made when the switch arm 72 is moved to engage the contact member B, in which case the current flows through the wires 83, 78, contact arm 94 which is held into engagement with the contact arm 95 by reason of the enlargement 96 of the contact arm resting on the periphery of the disk 91. The current now passes through the wire 97, into the clock, the return line of the circuit being through wires 98 and 33.

When the disk 91 moves to a position wherein the enlargement 96 may drop into the cutout portion 92, the contact arm 94 will move into engagement with the contact arm 99 completing a circuit through the wires 100 and 101, to the siren 102, the return line of the circuit being through the wire 103, and wire 33. Thus it will be seen that with each complete revolution of the disk 91, the siren will be sounded indicating that a quarter has been completed.

Should it be desired to take time out for any reason, the switch arm 106 is moved to engage its contact point and switch arm 72 is moved to engage the contact point 104 of the switch box, whereupon the circuit is completed to the siren through the wire 105, wire 101, the return line of the circuit being through wire 103 and wire 33. It will of course be understood that with the completing of the circuit to the siren, the circuit to the clock is automatically broken owing to the fact that the contact arms 94 and 95 are moved out of contact with each other. When the switch member 72 has been moved to engage contact 104 during time out, the score keeper may cause the siren to be sounded by operating the switch 106, whereupon the electric current flows through wire 14, through switch member 72, through switch member 106, wire 105, wire 101, through the siren and through wire 103 to the negative wire 33 of the circuit.

I claim:

In a display device, a housing, an indicating member operating within the housing, groups of distinctive lamp signals within the housing and adapted to illuminate the housing, a source of electricity supply, a constantly moving time controlled switch including a disk having an elongated notch in its periphery, spaced upper and lower stationary contact arms in circuit with the source of electricity supply, each of the contact arms being in circuit with a certain group of lamp signals, a movable contact arm having an enlargement adapted to engage the disk and move the movable contact arm into engagement with the upper stationary contact arm completing a circuit to certain lamp signals, and said enlargement adapted to move into the elongated notch, lowering the movable contact arm into engagement with the lower stationary contact arm completing a circuit to another group of signal lamps for a predetermined period.

RALPH ARTHUR NEVINGER.
